(57) **CLAIM**

The ornamental design for an assembly of golf tees with hanging hook, as shown and described.

DESCRIPTION

FIG. 1 is a perspective view of an assembly of golf tees with hanging hook showing my new design;

FIG. 2 is a top plan view thereof;

FIG. 3 is a front view thereof;

FIG. 4 is a left side view thereof;

FIG. 5 is right side view thereof;

FIG. 6 is a bottom plan view thereof;

FIG. 7 is a perspective view of a golf tee separated from the assembly of golf tees with hanging hook;

FIG. 8 is a top plan view thereof;

FIG. 9 is a bottom plan view thereof;

FIG. 10 is a side view of FIG. 7, wherein the opposite side view is a mirror image thereof; and,

FIG. 11 is a front view of FIG. 7, wherein the opposite view is a mirror image thereof.
